Primary Examiner — Robin V Webster*Assistant Examiner* — Keith J Wilson*(74) Attorney, Agent, or Firm* — Husch Blackwell LLP(57) **CLAIM**

The ornamental design for a “tailgate tent with stadium scene,” as shown and described.

DESCRIPTION

FIG. 1 is a perspective view of a tailgate tent with stadium scene, showing our new design;

FIG. 2 is a back view thereof;

FIG. 3 is a front view thereof;

FIG. 4 is a left view thereof;

FIG. 5 is a right view thereof;

FIG. 6 is a top side view thereof; and,

FIG. 7 is a bottom side view thereof.

The subject matter shown in dashed lines represents shading only and forms no part of the claimed design.
